(57) CLAIM

The ornamental design for a wheel, as shown and described.

DESCRIPTION

The device is a wheel for motorized vehicles like motorcycles, automobiles, and trucks.

FIG. 1 is a front view of a wheel, showing my new design;

FIG. 2 is a rear view thereof;

FIG. 3 is a side view thereof; and,

FIG. 4 is a front perspective view thereof.

The broken line showing of environment is for illustrative purposes only and forms no part of the claimed design.

1 Claim, 4 Drawing Sheets

FIG. 1

FIG. 2
